UNITED STATES PATENT OFFICE.

WALTER WILSON AND CHARLES T. MICHALIC, OF SAN FRANCISCO, CALIFORNIA.

CHANGEABLE ILLUMINATOR.

Application filed May 31, 1923. Serial No. 642,619.

To all whom it may concern:

Be it known that we, WALTER WILSON and CHARLES T. MICHALIC, citizens of the United States, residing at San Francisco, in the county of San Francisco and State of California, have invented certain new and useful Improvements in Changeable Illuminators; and we do declare the following to be a full, clear, and exact description of the invention, such as will enable others skilled in the art to which it appertains to make and use the same.

Our invention relates to illuminating devices and more particularly to one adapted for producing constantly changing color effects on stages, in halls, etc.

The principal object of the invention is to provide a simple yet effective device of the class set forth which will project constantly changing colored light rays and will continually change the directions in which the rays are projected.

In carrying out the above end, an oscillatory carrier is provided for a light ray projector and another carrier movable bodily with the first named carrier, is provided for successively presenting differently colored screens in the path of the projected light rays. Further objects are to provide novel means for producing the oscillatory motion of the first named carrier means and for simultaneously driving the second carrier.

With the foregoing in view, the invention resides in the novel subject matter herein-after described and claimed, the description being supplemented by the accompanying drawing.

Figure 1 is a side elevation partly in section of an illuminator constructed in accordance with our invention.

Figure 2 is a top plan view partly broken away and in horizontal section.

Figure 3 is a front end elevation.

Figure 4 is a vertical transverse sectional view as indicated by line 4—4 of Fig. 1.

The preferred form of construction selected for illustration in the present application, includes a base plate 1 having on one end a flat hollow gear casing 2, into which a pair of parallel vertical shafts 3 and 4 extend, the shaft 4 being preferably longer than the other shaft as shown. By suitable gearing 5 in the casing 2, the two shafts 3 and 4 are geared together and we provide any suitable means for driving the shaft 3, it being preferable to provide the upper end of this shaft

with a worm wheel 6 meshing with a worm 7 on a transverse shaft 8 which is mounted on the casing 2 in appropriate bearings, said shaft 8 being driven by a belt 9 from an electric motor 10.

An arched bearing support 11 rises from the front portion of the casing 2 and carries an upright tubular bearing post 12 into which the shaft 4 extends. At the upper end of the post 12, a horizontal sleeve 13 is disposed, said sleeve having a depending tubular bearing stub 14 which is turnably received in the upper end of the post. The sleeve 13 receives the rear end of a horizontal carrying arm 15 and a set screw 16 may well be threaded through said sleeve to hold the arm 15 therein. By means of a suitable hanger 17 which is preferably adjustable vertically, a light ray projector 18 is connected with the carrying arm 15. In front of this projector, we rotatably mount a carrying wheel 19 for a plurality of differently colored screens 20 which are adapted to be successively disposed in the path of the light rays projected from the projector 18. The wheel 19 is mounted for movement bodily with the arm 15 when the latter is oscillated and we prefer to employ a suitable stub shaft 21 for said wheel, secured to the projector 18.

For driving the carrying wheel 19, a belt 22 is engaged with its periphery and extends around a drive pulley 23 on a longitudinal shaft 24 which is rotatably mounted in a suitable bearing 25 carried by the upper side of the projector 18, the rear end of said shaft 24 being connected by a suitable coupling 26 to a flexible shaft 27 which extends along the carrying arm 15, being preferably received within a hollowed portion 28 thereof. The rear end of the shaft 27 turns downwardly through the bearing stub 14, into the bearing post 12, and is suitably secured to the upper end of the shaft 4. It will thus be seen that rotation of the last named shaft will slowly rotate the carrier 19.

For oscillating the arm 15 and parts carried thereby simultaneously with rotation of the carrying wheel 19 for the color screens, we have provided a longitudinal operating arm 29 below the arm 15, the front end of said arm 29 being received in a fork 30 or other guide which, in the construction shown, extends downwardly from the projector 18. The rear end of the arm 29 has a radially adjustable eccentric connection

31 with the worm wheel 6 and said rear end of the arm is provided with a longitudinal slot 32 through which the bearing post 12 extends. By this arrangement, it will be seen that rotation of the wheel 6 will cause oscillation of the operating arm 29 about the bearing 12 as a fulcrum, thus effecting similar oscillation of the arm 15 and the light ray-projecting means carried thereby.

10 To support the arm 29 against sagging, we have shown a suitable rest 33 carried by the casing 2, but other provision may of course be made for this purpose if desired.

When the motor 10 is driven, the shafting 4—27—24 is operated to drive the belt 22 and the screen carrier 19, thus successively presenting the differently colored screens 20 in the path of the projected light rays from the projector 18, to produce constantly changing color effects. Simultaneously with projection of these various colored lights, the arm 15 is slowly oscillated by the operating arm 29 so that the direction in which the colored rays are projected, is constantly changing, thus producing exceptionally pleasing illuminating effects.

As excellent results are obtainable from the details disclosed, they may be followed if desired, but within the scope of the invention as claimed, numerous minor changes may be made.

We claim:

1. A changeable illuminating device comprising a supporting member, means for moving said member alternately in opposite directions, a light ray projector carried by said supporting member and movable bodily therewith, a plurality of differently colored screens associated with said projector, and means operative during movement of said supporting member for successively presenting said screens to the projected rays from said projector.

2. A changeable illuminating device comprising a supporting member, means for moving said member alternately in opposite directions, a light ray projector carried by said supporting member and movable bodily therewith, a wheel in a plane transverse to the projected rays from said projector and movable bodily with said supporting member, said wheel having a plurality of differently colored screens for successive presentation to the projected light rays, and means for rotating said wheel during movement of said supporting member.

3. A changeable illuminating device comprising a carrying arm and means support-

ing the same for oscillation, a light ray projector carried by said arm, a plurality of differently colored screens and a carrier movable bodily with said arm for successively presenting said screens to the projected light rays, means for oscillating said arm, and means for driving the screen carrier while said arm is oscillating.

4. A changeable illuminating device comprising an upright post, a horizontally oscillating arm mounted on said post, a light ray projector carried by said arm, a plurality of differently colored screens and a carrier for successively presenting them to the projected rays from said projector, said carrier being bodily movable with said arm, and driving means for said carrier, including shafting extending upwardly through said post and along said arm.

5. An illuminating device comprising a post, an oscillatory arm mounted on said post for carrying an illuminator, an elongated operating arm for said carrying arm having near one end a longitudinal slot through which said post passes, means connected to said one end of said operating arm for oscillating the latter, and connecting means between the other end of said operating arm and said carrying arm for oscillating the latter.

6. A changeable illuminating device comprising a base, a pair of upright driven shafts geared together and extending upwardly from said base, one of said shafts having an eccentric on its upper end, a bearing post for the other shaft and a support for said post rising from the base, a horizontal carrying arm pivoted for horizontal movement on the upper end of said post, a light ray projector carried by said arm, a plurality of differently colored screens adapted for successive presentation to the rays projected from said projector and a rotatable carrier for said screens carried by said arm, means for driving said carrier from the aforesaid other shaft, including shafting extending along said carrying arm and into said bearing post, and a horizontal operating arm for said carrying arm having operative connection therewith at its front end, the rear end of said operating arm being connected operatively with the aforesaid eccentric and having a longitudinal slot receiving said bearing post.

In testimony whereof we have hereunto affixed our signatures.

WALTER WILSON,
CHARLES T. MICHALIC.
